(57) **CLAIM**

The ornamental design for a SSD storage device, as shown and described.

DESCRIPTION

FIG. 1 is a perspective view of SSD storage device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The appearance of the right side of the SSD storage device is the same as the left side, the only exception being the unclaimed oval port seen on the left.

The broken lines in the drawings depict a portion of the SSD storage device that forms no part of the claimed design.
